SPRING CLAMP

Oscar F. Tallman, St. Louis, Mo., assignor to
 James R. Kearney Corporation, St. Louis, Mo.,
 a corporation of Missouri

Application August 19, 1937, Serial No. 159,922

4 Claims. (Cl. 24—253)

This invention relates generally to clamps for electrically connecting grounding wires, tap wires, and other electrical conductors to power lines and the like, and more specifically to a clamp of this sort which is of the spring type as differentiated from the well known type of electrical clamp which includes jaws arranged for mechanical relative movement into clamping engagement with a power line or other electrical conductor, the predominant object of the invention being to provide an improved clamp of the spring type which though of extremely simple and inexpensive construction and arrangement is capable of performing its intended function in a highly efficient manner.

Fig. 1 is a side elevation of the improved clamp, the pole or clamp stick thereof being broken away to conserve space.

Fig. 2 is a front elevation of the clamp illustrated in Fig. 1.

Fig. 3 is a vertical section taken on line 3—3 of Fig. 2.

Fig. 4 is a horizontal section taken on line 4—4 of Fig. 2.

Fig. 5 is a view partly in plan and partly in horizontal section on line 5—5 of Fig. 1.

Fig. 6 illustrates a slightly modified form of the invention where the clamp is provided with a bar adapted to support associated clamps in cluster arrangement.

In the drawing, wherein are shown for the purpose of illustration, merely, two embodiments of the invention, A designates in Figs. 1 to 5, inclusive the improved clamp generally. The clamp A includes a head 1 which is in the general form of a ferrule into which an end portion of a pole or clamp stick 2 is extended as shown to the best advantage in Fig. 3, a transversely extended pin 3 being passed through opposed apertures formed in the wall of the head 1 and through an opening formed through the pole on clamp stick 2 so as to securely fix said head to said pole or clamp stick. The head 1 includes an upwardly projected extension 4, which as shown clearly in Fig. 5 is hollow and preferably is of elliptical shape when viewed in horizontal section, said extension being located at one side of the head 1 and the top wall 1' of the head which leads to the base of the extension being inclined upwardly toward said base of said extension.

Supported by the head 1 is an element 5 which serves as one of the clamping members of the clamp A, said element including a pair of parallel portions 5a (see Fig. 5) which are extended

into the hollow extension 4 of the head 1. The interior dimensions of the hollow extensions are slightly greater than the combined dimensions of the parallel portions 5a of the element 5 so that a space is provided between the inner wall 5 of the hollow extension and the outer surfaces of said parallel portions, and a body of anchoring material such as solder, lead, or other suitable material 6 is introduced, preferably in a molten or plastic condition, into said space and 10 thereafter hardens therein. The upper end face of the pole or clamp stick provides the lower wall of the space into which the anchoring material 6 is introduced, and said space extends laterally beneath the inclined top wall of the 15 head 1 as clearly illustrated in Fig. 3. The entire space described above is filled by the body of anchoring material 6 and the lower end portions of the parallel portions of the element 5 are split and spread outwardly as indicated at 20 5b in Fig. 3 so as to effectively anchor the parallel portions 5a of the element 5 in the hollow extension 4 of the head 1.

The element 5 is preferably made in two parts of similar shape, each part including one of the 25 lower portions 5a, a lower outwardly extended portion 5c, a vertically extended portion 5d, and an upper inwardly extended portion 5e. The vertical portions 5d of the element 5 are arranged in opposed parallel relation and the inwardly extended portions are projected toward each other preferably with a slight space between the adjacent inner end faces of said inwardly extended portions as shown by dotted lines in Fig. 2.

Mounted at the upper end of the element 5 is a tubular member 7 which is split longitudinally from end to end at the bottom thereof. By referring to Fig. 4 it will be noted that the split at the bottom of the tubular member 7 is in the form of relatively wide opening portions 8 extended inwardly from the opposite ends of said tubular member, and these relatively wide opening portions are joined by a narrower intermediate opening portion 9. The tubular member 7 is assembled with the upper portion of the element 5 by introducing the inwardly extended portions 5e into the hollow interior of said tubular member, the extreme upper end portions of the opposed vertical portions 5d of said element 5 being disposed in the wider opening portions 8 of the split at the bottom of said tubular member as shown in Figs. 2 and 4 whereby the tubular element is prevented from rotating.

The clamp A includes a second clamping mem-

35

50

55

ber 10 which is preferably formed from a single length of material. The clamping member 10 is provided with spaced apart eyes 11 which embrace the tubular member 7, and slightly curved portions 12 extend downwardly from said eyes in convergent relation to a point approximately midway of the length of the clamping member. The lower portion of the clamping member 10 takes the form of a narrow loop 13 which extends 5 downwardly and inclines outwardly from the lower ends of the convergent portions 12. Because of the presence of the eyes 11 embracing the tubular member 7 the clamping member 10 is capable of arcuate swinging movement about 10 said tubular member.

The improved clamp is provided with a spring element 14 which includes a portion that is wound spirally about the tubular member 7 as is shown to the best advantage in Fig. 3, said 20 spiral portion 14a being provided at the inner end thereof with a lip 14b which is extended into the opening portion 9 of the split at the bottom of the tubular member 7 so as to anchor said inner end of the spiral portion of the spring 25 element to the tubular member. The spring element includes also a downwardly and outwardly projected extension 15 which contacts with the clamping member 10 in the manner illustrated in Figs. 1, 2, and 3, said extension of the spring 30 element also being provided with a lip 16. The winding of the spiral portion of the spring element is such that the lower end of the extension 15 thereof tends to move the clamping member 10 toward the element 5 which provides the associated clamping member of the clamp. As 35 shown in Figs. 2 and 4 the spring element 4 is of substantial width and the spiral portion of said spring element is disposed about the tubular member 7 of the clamp at a point between the eyes 11 of the movable clamping member 10.

The head 1 is provided with a laterally projected extension 17 which has an opening 18 formed therein, said opening being of approximately semicircular shape as shown by dotted lines in Fig. 5. This opening is open at one side face of the extension, and at the opposite side face thereof a relatively small opening 19 is provided which communicates with the opening 18. The shank portion of a bolt 20 is extended through the opening 19 and this bolt is provided with an eye 21 which is partially disposed in the semicircular opening 18, said shank portion of said bolt having a nut 22 mounted thereon which may be manipulated to draw the eye of the bolt inwardly of the semicircular opening 18. The extension 17 is provided with wire seats 23 (Fig. 5) above and below the semicircular opening 18 and the eye 21 of the bolt 20 is provided with 50 upwardly and downwardly extended projections 24 which are likewise provided with wire seats 25. When it is desired to attach a ground wire or other electrical conductor to the clamp an end portion of such wire is introduced between 55 the wire seats of the extension 17 and the projections 24 of the eye of the bolt 20. The nut of the bolt is then rotated to draw the eye of the bolt inwardly of the semi-circular opening 18 whereby said wire is clamped between said wire seats as shown by dotted lines in Fig. 5, wherein 60 the grounding wire or other electrical conductor is designated by the reference character 26.

When in the use of the improved clamp it is desired to apply same to a power line or other 65 electrical conductor the clamp, with a ground 70

wire or other conductor attached thereto, is elevated with the aid of the pole or clamp stick forming a part thereof until the lower end portion 13 of the clamping member 10 may be passed over the power line or other electrical conductor. When the clamp has been so positioned that the power line or other electrical conductor is located in the crotch formed by the downwardly and outwardly inclined lower portion 13 of the clamping member 10 and the adjacent face of the extension 4 of the head 1, the clamp is pulled downwardly. Such downward pull on the clamp will force the clamping member 10 outwardly against the action of the spring element 14 and said downward pull on the clamp is continued until the power line or other electrical conductor is properly clamped between the outwardly curved portions 27 of the clamping member 10 and adjacently located portions of the vertical portions 5d of the element 5 as shown by dotted lines in Fig. 1, wherein the power line or other electrical conductor is shown by dotted lines and is designated by the reference character 28.

The form of the improved clamp illustrated in Fig. 6 includes a cluster bar 29 which extends outwardly in opposite directions from the head 1 thereof. This cluster bar is intended to receive and support other clamps of the improved construction when it is desired to use the clamps in cluster assembly.

I claim:

1. A clamp comprising a fixed clamping member formed from elongated material bent to provide the fixed clamping member with opposed side portions and a transverse portion located between the upper ends of said opposed side portions, a movable clamping member formed from elongated material bent to provide opposed portions provided with eyes at their upper ends which embrace said transverse portion of said fixed clamping member to pivotally attach said movable clamping member to said fixed clamping member, a spring element wound spirally about said transverse portion of said fixed clamping member and provided with a portion extended from said spirally wound portion which engages said movable clamping member, and means fixedly supported by said transverse portion of said fixed clamping member and arranged in engagement with said spring element for anchoring said spring element to said transverse portion of said fixed clamping member.

2. A clamp comprising a fixed clamping member formed from elongated lengths of material bent to provide the fixed clamping member with opposed side portions and inwardly extended portions at the upper ends of said opposed side portions, a movable clamping member formed from an elongated length of material bent to provide opposed portions provided with eyes at their upper ends which embrace said inwardly extended portions of the fixed clamping member to pivotally attach said movable clamping member to said fixed clamping member, a spring element wound spirally about said inwardly extended portions of the fixed clamping member and provided with a portion extended from said spirally wound portion which engages said movable clamping member, and means fixedly supported by said inwardly extended portions of said fixed clamping member and arranged in engagement with said spring element for anchoring said spring element to said inwardly extended portions of said fixed clamping member.

3. A clamp comprising a fixed clamping member formed from elongated lengths of material bent to provide the fixed clamping member with opposed side portions and inwardly extended portions at the upper ends of said opposed side portions, a tubular element non-rotatably supported by and embracing said inwardly extended portions of said fixed clamping member, a movable clamping member formed from an elongated length of material bent to provide opposed spaced apart portions provided with eyes at their upper ends which embrace said tubular element, and a spring element wound spirally about said tubular element and provided with a portion extended from said spirally wound portion which engages said movable clamping member.
4. A clamp comprising a fixed clamping member formed from elongated material bent to pro-

vide the fixed clamping member with opposed side portions and a portion disposed between the upper ends of said opposed side portions, a tubular element non-rotatably supported by and embracing said portion of said fixed clamping member which is disposed between the upper ends of the opposed side portions thereof, a movable clamping member formed from an elongated length of material bent to provide opposed spaced apart portions provided with eyes at their upper ends which embrace said tubular element, and a spring element wound spirally about said tubular element and provided with a portion extended from said spirally wound portion which engages said movable clamping member.

OSCAR F. TALLMAN.
